UNITED STATES PATENT OFFICE.

JOSEPH R. MYERS AND BENJAMIN R. MYERS, OF CHICAGO, ILLINOIS.

HAT-TIP.

SPECIFICATION forming part of Letters Patent No. 714,731, dated December 2, 1902.

Application filed January 30, 1902. Serial No. 91,889. (No model.)

To all whom it may concern:

Be it known that we, JOSEPH R. MYERS and BENJAMIN R. MYERS, citizens of the United States of America, and residents of 146 North 5 Wood street, Chicago, Cook county, State of Illinois, have invented a new and useful Improvement in Hat-Tips, of which the following is a specification.

This invention relates to hat-tips, and comprises means to form a pocket in the tip or lining of a hat to receive a mirror and other articles, if desired.

In the accompanying drawings, Figure 1 is a plan view of a hat lining or tip provided 15 with our improvement. Fig. 2 is a plan view of the pocket detached before the retaining-cord is drawn. Fig. 3 is an enlarged cross-section on the line 3 3 of Fig. 2.

The pocket is formed of a band or strip of 20 cloth *a*, which is folded to receive and contain a running elastic gathering-cord *c* at the inner edge thereof and sewed around at its outer edge to the tip or lining *e*.

A mirror is indicated at *d*, and it is retained in the pocket by drawing the cord *c* and 25 gathering the band *a* in over the edge of the mirror and tying the ends of the cord. A comb, as *b*, or other article may be readily inserted in the pocket.

In hats having no lining the band is at- 30 attached to a piece of cardboard or similar backing, which may then be cemented to the inside of the hat.

What we desire to secure by Letters Patent is—

A hat-tip comprising a lining, the band *a* attached at its outer edge thereto, and the elastic gathering-cord *c* at the inner edge of the band, substantially as described.

JOSEPH R. MYERS.
BENJAMIN R. MYERS.
